UNITED STATES PATENT OFFICE.

EMIL W. MUNDT, OF BERNARDSVILLE, NEW JERSEY.

SPADE.

1,423,775.

Specification of Letters Patent. Patented July 25, 1922.

Application filed May 24, 1920. Serial No. 383,786.

To all whom it may concern:

Be it known that I, EMIL W. MUNDT, citizen of the United States, residing at Bernardsville, in the county of Somerset and 5 State of New Jersey, have invented certain new and useful Improvements in Spades, of which the following is a specification.

This invention has relation to digging tools and has for an object to provide an improved 10 spade wherein the blade is formed of a single piece and having as its main characteristic a back reinforced edge which is formed by beveling or bending the material of the blade upon itself, thus decreasing the 15 cost of manufacture of such tool.

In addition to the foregoing this invention comprehends improvements in the details of construction and arrangement on parts to be hereinafter described and particularly set forth in the appended claim.

In the accompanying drawings in which similar and corresponding parts are designated by the same characters of reference throughout the several views in which they 25 appear.

Figure 1 is a view in perspective of a digging tool constructed in accordance with my invention.

Figure 2 is a fragmentary view in edge 30 elevation, and

Figure 3 is a fragmentary view in rear elevation of the blade.

With reference to the drawings, 10 indicates the blade of a digging tool, as illustrated in the drawings preferably in the form of a spade. The material of the back edge is cut away at 11 at a point intermediate the side edges of the blade and the portion of the back edge thus left is bent back- 35 ward at the point 12, and again forward at the point 13, the point of flexure at both ends being arranged in such a manner that the distance between the point of flexure 12 and the point of flexure 13 is equaled to the 40 distance between the point of flexure 12 and the extreme terminal edge of the blade. It is also preferred that the bent edge of the blade be curved transversely as shown in Figure 2. A means for connecting the handle to the blade is provided in the nature of a plate 14 which is secured to the rear side 45 of the blade by means of the rivets 15, braz-

ing, or any other manner and said plate is then formed with a semicircular sleeve 16 by bending the material around a mandrel 55 or other object, permitting said sleeve 16 to project through the cut-away portion 11 of the back edge of the blade. This structure is duplicated at the front of the blade and the edges of the semicircular sleeve 16 are 60 crimped together forming a tubular sleeve. A wooden handle or the like 17 is then inserted in the sleeve 16 and held in any suitable manner. Thus, it will be seen that I have provided a blade which may be formed 65 primarily in one piece, and by means of a die thus eliminating the necessity of forming the blades in layers or sections in the manner heretofore adopted. A considerable saving of labor is effected by the use of the 70 method of forming the blade described above, in addition to the durability ensured by the sleeve arrangement described, strengthening, as it does the point of connection between the blade and handle. 75

While I have illustrated and described my invention with some degree of particularity, I realize that in practice various alterations therein may be made. I therefore reserve the right and privilege of changing the 80 form or the details of construction or otherwise altering the arrangement of the correlated parts without departing from the spirit of the invention or the scope of the 85 appended claim.

Having thus described my invention, what I claim as new and desire to secure by United States Letters Patent is:—

A spade, comprising the blade having its upper edge cut away at a point intermediate the side edges of the blade to form a recess, the remaining portions of the upper edge of the blade being curved and bent at right angles, and said bent portion again bent upon itself to define a curved, heel engaging reinforced upper edge for the blade, a pair of concave plates applied, one to each side of the blade with their concave sides directed toward each other and in registration with the recess, and a handle entering said 90 recess and the space between said concave plates. 95

In testimony whereof I affix my signature.
EMIL W. MUNDT.
